UNITED STATES PATENT OFFICE.

GEORGE PEACOCK, OF SELMA, ALABAMA.

LUBRICATING DEVICE FOR WHEELS.

SPECIFICATION forming part of Letters Patent No. 293,070, dated February 5, 1884.

Application filed December 14, 1883. (No model.)

To all whom it may concern:

Be it known that I, GEORGE PEACOCK, a citizen of the United States, residing at Selma, in the county of Dallas and State of Alabama, have invented certain new and useful Improvements in Lubricating Devices for Wheels, of which the following is a specification, reference being had therein to the accompanying drawings.

10 My invention relates to lubricating devices for wheels, drums, or pulleys, but will be herein described with reference to its construction and use in wheels. The object I have in view is to provide an oil-reservoir around or in connection with the box or hub, which shall automatically pay out the oil to the axle in suitable quantities, and shall at the same time be closed in such manner as to entirely preclude the possibility of leakage after 15 the oil has once been placed in it.

In the accompanying drawings, making part of this specification, Figure 1 represents a side view of a wheel with box introduced. Fig. 2 is a longitudinal section of the box, showing 20 its internal construction. Fig. 3 is a plan view of the cap or top to the oil-reservoir; and Fig. 4 is a perspective of a plug that closes the orifice, with key for operating it.

In the figures, A represents a wheel, which 25 is made of cast metal—hub, spokes, rim, and all—in one piece. The hub consists of a metallic sleeve, B, for receiving and retaining the box C. The interior of the hub and the exterior of the box are made tapering. The 30 box fitting within the hub is held in place by a series of bolts, which pass through openings, partially in the hub and partially in the box, acting like keys, but drawing the parts together by nuts on their ends. The box C has 35 cast within it an annular reservoir, D, which has a longitudinal opening cut in its upper side, said opening being covered by a removable top K.

J represents a screw, which fastens the top 40 in place, the sides of the head of said screw resting upon a soft-metal packing to prevent leakage.

E represents a short hollow barrel, which is provided with a flange, F, a spline, H, an

orifice, L, above the flange, and at its bottom 50 a stem, G. The upper end of the barrel, E extends through an opening in the top or cover K, and the spline H is allowed to play in a slot, x, in one side of said opening when the barrel moves up or down. When the barrel 55 has been pressed downward as far as it will go and is partially revolved, the spline H, having passed below its slot, catches against the under side of the cover K and holds it down. The stem G enters between the coils of a spiral spring, a, which is placed under it, said spring serving to actuate the barrel outward 60 when free. The flange F has its upper side provided with a suitable packing or gasket, and when the barrel is freed and the spring 65 presses it upward, the flange, with its packing, acts as a valve to shut off the escape of oil from the reservoir. The oil passes down through the barrel, and thence, when it is pressed down, through the orifice L into the 70 reservoir. The mouth of the barrel is made square inside, so that it can be operated by a wrench constructed as represented by P.

e represent oil-cups, which are situated in reservoir D, and over small openings which lead 75 from said reservoir to the axle of the wheel. The mouths of these cups reach almost to the under side of the cover K, the cups being filled with wool or cotton or other suitable fibrous material for the purpose of conveying the oil 80 slowly, and in small quantities but regularly, to the axle.

When the wheel is running, it causes an agitation of the oil, so as always to keep the packing in the cups properly supplied.

Having thus fully described my invention, what I claim, and desire to secure by Letters Patent, is—

1. The box C of a hub, cast with an annular oil-reservoir within it, the said reservoir being 90 provided with cups having ducts at their bottoms, through which the oil is conveyed to the axle, in combination with the removable top, the whole arranged substantially as and for the purposes specified.

2. The combination, with the hub having an annular reservoir, D, of the hollow barrel E, provided with a flange, F, a spline, H, and

an orifice, L, above the flange, and at its bottom with a stem, G, setting in the upper end of a spiral spring, a, substantially as and for the purposes specified.

5 3. In combination with the oil-reservoir in the box, a hollow barrel, E, having a spline, H, a feeding-orifice, L, and a packed valve, F, the barrel being actuated longitudinally

and outward by means of a suitable spring, substantially as described.

In testimony whereof I affix my signature in presence of two witnesses.

GEORGE PEACOCK.
